FOREIGN PATENT DOCUMENTS

CN 3679915 8/2007

Primary Examiner — Khawaja Anwar*Assistant Examiner* — Megan Tiana Rakos(74) *Attorney, Agent, or Firm* — Muncy, Geissler, Olds & Lowe, P.C.**CLAIM**

The ornamental design for a multi-function hub, as shown and described.

DESCRIPTION

FIG. 1 is a front right bottom perspective view of a multi-function hub showing our new design;

FIG. 2 is a front bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings are for the purpose of illustrating portions of the multi-function hub which form no part of the claimed design.

1 Claim, 8 Drawing Sheets(56)
